BELT CONVEYER SYSTEM

John T. Needham, North Plainfield, N. J., assignor to General Conveyors Limited, Montreal, Quebec, Canada, a corporation of Canada

Application June 6, 1930, Serial No. 459,507
Renewed July 8, 1932

32 Claims. (Cl. 198—165)

This invention relates more particularly to belt systems for conveying dispatch sheets in telegraph offices or the like. Important objects of the invention are, to provide a generally improved belt system of this character; to provide a belt system designed for operation at high speed; to provide a reliable belt system designed for a more positive and safe transmission of the dispatch sheets or other conveyed articles; to provide improved junctures between several cooperating belt lines; to provide a satisfactory juncture between a pick-up belt line and a feed line delivering to the pick-up line at an intermediate point in the latter; to provide means for a more satisfactory discharge of the dispatch sheets from the conveyor system; and to provide other improved features of design which will be described herein-after.

In the drawings:

Fig. 1 is a diagrammatic perspective view showing the general layout of the belt system;

Fig. 2 a vertical section taken through the system, on the line 2—2 of Fig. 4;

Fig. 3 a side elevation showing the power transmission means at one of the belt junctures;

Fig. 4 a vertical section taken through the system, on the line 4—4 of Fig. 2;

Fig. 5 a perspective view of a juncture between a feed line and a pick-up line;

Fig. 6 a horizontal section taken on the line 6—6 of Fig. 3;

Fig. 7 a side view of the belt discharge means for the system;

Fig. 8 a section taken on the line 8—8 of Fig. 7;

Fig. 9 a section taken on the line 9—9 of Fig. 8; and

Fig. 10 a side view of one of the feed line junctures.

As shown diagrammatically in Fig. 1, my belt system includes a plurality of parallel feed lines 1 all disposed at the same level. At an overhead level is a pick-up line 2 extending transversely with respect to said feed lines. From an intermediate point in each feed line 1 a vertical feed line 3 leads upward to the pick-up line. Each feed line is adapted to be fed at a plurality of points therealong with dispatch sheets or other articles to be conveyed, and conveyor belts carry the deposited sheets inwardly in opposite directions along the lines 1, upwardly along the lines 3 and along the line 2 to a discharge point. In the use of the system in a telegraph office or the like, the operators will be seated along both sides of each feed line 1, at positions adjacent the said feed points.

The various belt lines of the system are supported by skeleton frames. Each line 1 has a frame 4 formed by four longitudinal members 5 connected by transverse members 6 and defining a rectangular space therebetween in cross section. Standards 7 support said frame at a suitable elevation. The frame 8 of the pick-up line 2 is similarly formed of four longitudinal members 9 connected by transverse members 10. Each vertical line has a frame 11 extending from the floor to the ceiling and intersecting the pick-up frame and also one of the feed line frames. The vertical frame 11 is also formed of long vertical members 12 connected by transverse members 13 and secured at their upper and lower ends to the ceiling and floor respectively.

Each feed line 1 is divided by its connected vertical line 3 into two sections which are in effect branches of line 3. Extending inward along each branch from the outer end thereof to line 3 are conveyor belts. Long endless belts 14 extend along the length of the branches within the frame 4 and are trained over pulleys 15 spaced therealong and over inner end pulleys 16 and 17 at the intersection of lines 1 and 3. Pulleys 16 are disposed above the level of pulleys 15 and close together within the vertical frame 11, and pulleys 17 are spaced slightly below the level of pulleys 15 and outwardly of pulleys 16. Thereby the belts 14 of the two branches are trained to converge upwardly at the juncture of lines 1 and 3. The upper strand 14^a of each belt 14 is in direct contact with the pulleys 15 and the under strand travels over an intermediate pulley 18. Above each long belt 14 is a series of shorter endless belts 19 arranged in succession along said long belt and trained over pulleys 20 so that their understrands 19^a are in face to face contact with the upper strand 14^a of belt 14. Pulleys 20 are disposed intermediate the pulleys 15 and at such a level with relation to the latter as to train the strands 14^a and 19^a along a slightly zig-zag course so as to hold said strands in close contact. These contacting strands are adapted to hold the dispatch sheets therebetween and convey them to the vertical line 3. At the outer end of each branch the adjacent pulleys 15 and 20 and the belts trained over them define a flaring mouth 21 through which the dispatch sheets are fed between the contacting conveyor strands. Other mouths 22 are defined at intermediate points along the line by adjacent pulleys 20 and the successive belts 19. Over each mouth 21 and 22 is mounted a small hopper 23 to receive the sheets and direct them into the mouth.

59^a of belt 59 will deflect it from said belt 25 and cause it to drop in between the strands 58^a and 59^a. The strands 58^a and 59^a do not grasp the dispatch sheets until they have been dropped into 5 the tapered chute between said strands, so that the auxiliary delivery belts 58 and 59 may be driven at a much lower speed than the main pick-up line belts 25 and 32. The crowned and grooved discharge pulleys 56 and 57 crimp or bend the 10 sheets so that they will not stick to belts 58 and 59.

The belts of the pick-up line 2 are driven by a single electric motor 62 which has a belt driving connection 63 with a pulley 64 fixed to the shaft 15 65 of pulley 29 at the discharge end of the pick-up line. Thereby, the long belt 25 which extends the entire length of the pick-up line is directly driven. Said belt through the frictional contact of its under strand 25^a with the upper 20 strands 38^a of the shorter belts 30 serves to drive the latter belts. In the same manner the belt 32 is driven. There are also driving connections linking up the successive belts 30 and also the belt 32 across the junction gaps. These driving 25 connections are formed by sprocket wheels 66 fixed to the shafts 31^a of the pulley 31 and by driving chains 67 connecting said sprocket wheels across the gaps. These chain drives have been omitted 30 from Fig. 4 to avoid confusion.

30 The belts of the vertical feed lines 3 and of the horizontal feed lines 4 are preferably driven independently of the pick-up line 2 by motors 68. Each of said motors drives the belts of one vertical feed line and its connected horizontal feed 35 line and is mounted in any convenient position, as within the upper end of the supporting frame 11 of the vertical line. Upon the motor shaft is fixed a pulley 69 and upon the shaft 42^a of pulleys 42 and 58 is fixed a pulley 70. Trained around said pulleys is a driving belt 71. A gear 72 is also fixed upon shaft 42^a and meshes with a gear 73 of the same diameter fixed upon the shaft 41^a of the pulley 41. Thereby, belts 36 and 37 of the vertical line are driven at the same speed and their opposed cooperating strands 36^a and 37^a travel in the same direction. At the lower end of the vertical line the shaft 38^a of each pulley 38 has fixed to it a gear 74 which meshes with a gear 75 of the same diameter, fixed to the shaft 16^a of the adjacent pulley 16. Thereby each of the belts 36 and 37 drives one of the horizontal belts 14, and each belt 14 drives its cooperating belts 19 by frictional contact.

55 Throughout the system the pulleys of the various conveyer belts are rotatably supported by shafts which are suitably supported by the skeleton frames. Preferably these pulleys are all of the same diameter. The belts are preferably of a narrow flat type, belts only two inches in width having been found satisfactory. It is possible also to employ cords or the like in place of belts. Therefore in the claims, the term "belt", unless qualified, is to be construed in its broadest sense to include cords or similar equivalents.

60 In the operation of the belt system, operators stationed along the feed lines 4 will deposit the dispatch sheets in the hoppers 23 by which they are delivered into the mouths 21 or 22 and thence between the opposed, cooperating traveling belt strands 14^a and 19^a by which they are gripped and conveyed to the juncture between the horizontal feed line and the vertical feed line. Here they are delivered into the inverted V-shaped mouth 40 and thence between the opposed co-

operating belt strands 36^a and 37^a which grip them and convey them to the juncture of the vertical line with the pick-up line where they are delivered to the narrow, obliquely disposed transfer belts 52. The latter deliver the sheets upwardly and forwardly and the guide plate 53 guides them between the opposed cooperating strands 25^a and 38^a (or 25^a and 32^a) by which they are gripped and conveyed along the pick-up line and downward to the discharge belts 58 and 59 which strip them from the conveyer belts and discharge them at a reduced speed, to avoid disturbance at the discharge point and prevent the sheets from flying about. Sheets which are required to pass one or more feed line junctures in 15 their travel along the pick-up line are conveyed across said junctures without interruption by the narrow auxiliary belts 49 cooperating with the long belt strands 25^a. A sheet is in fact conveyed without interruption from any one of the feed points to the discharge point.

When it is required to cut out any one of the feed lines for the purpose of repairing or replacing one of its belts the motor 68 driving said line is stopped. The drive of the vertical 25 feed line and its connected horizontal feed line is then stopped without affecting the drive of the pick-up line. The motors 68 are controlled by switches 76 which are mounted within convenient reach of the operators and have electrical connections with the motors as indicated at 77. The motor 62 of the pick-up line is independently controlled by a switch 78.

The design of the system provides for the safe and positive transmission of dispatch sheets or other flat articles by means of very narrow belts. Thereby a much greater delivery speed may be attained owing to the fact that less driving power is required, belt friction is reduced and less static is developed. Furthermore both the 40 first cost and the maintenance of the system are materially reduced by the use of narrow belts and pulleys. The design also provides entirely satisfactory transfer junctures between conveyer lines meeting at an angle. Another advantage which the system possesses is the visibility and accessibility of the conveyer belts. They are all exposed so that any obstruction or other trouble in the conveyer lines can be readily seen and corrected.

50 While I have shown and described a very satisfactory form of my invention I do not wish to be limited strictly to this disclosure but reserve the right to make such changes as will lie within the scope of the claims.

55 What I claim is:

1. In a belt conveyer system, a conveyer line comprising a plurality of endless conveyer belts, and pulleys training said belts to present cooperating strands arranged in opposed relation for holding articles therebetween and conveying them along the line; means to drive said belts and move the cooperating strands in the same direction and at the same speed; a plurality of relatively small pulleys driven with the first mentioned pulleys of said conveyer belts at the discharge end of the line; a plurality of larger pulleys spaced from the discharge end; and endless belts trained around said small and large pulleys and adapted to receive articles, therebetween from the discharge end of the line, deflect them from said conveyer belts and discharge them from between the larger pulleys at a speed slower than their rate of travel along the conveyer line.

2. In a belt conveyer system, an overhead pickup conveyer line comprising a plurality of endless belts trained to provide a relatively long reach of one belt and a series of directly opposed and shorter reaches of other belts therebelow juxtaposed end to end to coact therewith to grip and transport articles and to define a plurality of downwardly facing mouths for entry of articles into the pick-up conveyer line, means for driving said belts to cause said coacting relatively long belt reach and shorter belt reaches to travel in the same direction, a plurality of feeder conveyer lines each associated with a different one of said downwardly facing entry mouths of said overhead pick-up conveyer line and each comprising a pair of endless belts having upwardly extending opposed coacting article-gripping and conveying reaches terminating at one of said mouths, and means for driving the belts of the feeder lines in directions causing said coacting reaches of each feeder line to deliver articles gripped therebetween to the associated entry mouth of the pick-up line.

3. In a belt conveyer system, an overhead pick-up conveyer line comprising a plurality of endless belts trained to provide a relatively long reach of one belt and a series of directly opposed and shorter reaches of other belts therebelow juxtaposed end to end to coact therewith to grip and transport articles and to define a plurality of downwardly facing mouths for entry of articles into the pick-up conveyer line, means for driving said belts to cause said coacting relatively long belt reach and shorter belt reaches to travel in the same direction, a plurality of feeder conveyer lines each associated with a different one of said downwardly facing entry mouths of said overhead pick-up conveyer line and each comprising a pair of endless belts having upwardly extending opposed coacting article-gripping and conveying reaches terminating at one of said mouths, and means for driving the belts of the feeder lines in directions causing said coacting reaches of each feeder line to carry articles gripped therebetween to the associated entry mouth of the pick-up line, and transfer means for directing articles laterally from the feeder lines into the pick-up line in the general direction of conveyance of articles by the pick-up line.

4. In a belt conveyer system, an overhead pickup conveyer line comprising a plurality of endless belts trained to provide a relatively long reach of one belt and a series of directly opposed and shorter reaches of other belts therebelow juxtaposed end to end to coact therewith to grip and transport articles and to define a plurality of downwardly facing mouths constantly open for entry of articles into the pick-up conveyer line, means for driving said belts to cause said coacting relatively long belt reach and shorter belt reaches to travel in the same direction, a plurality of feeder conveyer lines each associated with a different one of said downwardly facing entry mouths of said overhead pick-up conveyer line and each comprising a pair of endless belts having upwardly extending opposed coacting reaches terminating at one of said mouths, means for driving the belts of the feeder lines in directions causing said coacting reaches of each feeder line to deliver articles gripped therebetween to the associated entry mouth of the pick-up line, and means for directing articles moving along the pick-up line across the entry mouth gaps between adjacent ends of the shorter belt reaches

of said pick-up line and permitting constant entry of articles to the pick-up line through said gaps.

5. In a belt conveyer system, an overhead pickup conveyer line comprising a plurality of endless belts trained to provide a relatively long reach of one belt and a series of directly opposed and shorter reaches of other belts therebelow juxtaposed end to end to coact therewith to grip and transport articles and to define a plurality of downwardly facing mouths for entry of articles into the pick-up conveyer line, means for driving said belts to cause said coacting relatively long belt reach and shorter belt reaches to travel in the same direction, a plurality of feeder conveyer lines each associated with a different one of said downwardly facing entry mouths of said overhead pick-up conveyer line and each comprising a pair of endless belts having upwardly extending opposed coacting reaches terminating at one of said mouths, means for driving the belts of the feeder lines in directions causing said coacting reaches of each feeder line to deliver articles gripped therebetween to the pick-up line, and means whereby any feeder line may be put out of action without affecting operation of the other feeder lines and the pick-up line.

6. In a belt conveyer system, an overhead pickup conveyer line comprising a plurality of endless belts trained to provide a relatively long reach of one belt and a series of directly opposed and shorter reaches of other belts therebelow juxtaposed end to end to coact therewith to grip and transport articles and to define a plurality of downwardly facing mouths for entry of articles into the pick-up conveyer line, means for driving said belts to cause said coacting relatively long belt reach and shorter belt reaches to travel in the same direction, a plurality of feeder conveyer lines each associated with a different one of said downwardly facing entry mouths of said overhead pick-up conveyer line and each comprising a pair of endless belts having upwardly extending opposed coacting reaches terminating at one of said mouths, and individual motors for driving the several feeder lines, the driving means for the pick-up line comprising a motor individual to said pick-up line.

7. In a belt conveyer system, pairs of article receiving and conveying feeder lines, a main article conveying line, the feeder lines of each pair having their delivery ends juxtaposed, connecting conveyer lines each extending from the delivery point of one pair of feeder lines to a different point on the main line, said feeder lines and said main line each comprising a plurality of endless belts one of which has a reach extending to the delivery point and the others of which each has a shorter reach opposed to said first-mentioned reach with said shorter belt reaches juxtaposed end to end for insertion of articles into said feeder and main lines between the adjacent ends of said shorter belt reaches, said connecting lines each comprising a pair of belts having coactive opposed reaches arranged for receiving articles discharged from its associated pair of feeder lines and delivering the same to its associated article insertion point of the main line, and means for driving all the belts in directions to convey articles inserted in the several feeder lines to the discharge point of the main line.

8. In a belt conveyer system, pairs of article receiving and conveying feeder lines, a main article conveying line, the feeder lines of each pair having their delivery ends juxtaposed, con-

necting conveyer lines each extending from the delivery point of one pair of feeder lines to a different point on the main line, said feeder lines and said main line each comprising a plurality of endless belts one of which has a reach extending to the delivery point and the others of which each has a shorter reach opposed to said first-mentioned reach with said shorter belt reaches juxtaposed end to end for insertion of 5 articles into said feeder and main lines between the adjacent ends of said shorter belt reaches, said connecting lines each comprising a pair of belts having coactive opposed reaches arranged for receiving articles from its associated pair of 10 feeder lines and delivering the same to its associated article insertion point of the main line, and driving means for driving the belts to convey articles to the discharge point of the main line and including means whereby the respective 15 connecting lines with their associated feeder lines may be put out of action individually.

9. In a belt conveyer system, pairs of article receiving and conveying feeder lines, a main article conveying line, the feeder lines of each 20 pair having their delivery ends juxtaposed, connecting conveyer lines each extending from the delivery point of one pair of feeder lines to a different point on the main line, said feeder lines and said main line each comprising a plurality 25 of endless belts one of which has a reach extending to the delivery point and the others of which each has a shorter reach opposed to said first-mentioned reach with said shorter belt reaches juxtaposed end to end for insertion of 30 articles into said feeder and main lines between the adjacent ends of said shorter belt reaches, said connecting lines each comprising a pair of belts having coactive opposed reaches arranged for receiving articles from its associated pair of 35 feeder lines and delivering the same to its associated article insertion point of the main line, means for driving the main conveyer line, and individual driving means for each connecting conveyer line and its associated pair of feeder 40 lines.

10. In a belt conveyer system, a pair of article receiving and conveying feeder lines extending toward each other from opposite directions and having their delivery ends juxtaposed, each line 45 comprising a plurality of endless belts one of which has a reach extending to the delivery point and the others of which each has a shorter reach opposed to said first mentioned reach with said shorter belt reaches juxtaposed end to end for insertion of articles into said feeder lines between the adjacent ends of said shorter belt reaches, and a belt conveyer line leading transversely from the juxtaposed ends of said feeder lines and comprising a pair of belts having co- 50 active opposed reaches arranged for receiving articles from said feeder lines and conveying them away from the latter.

11. In a belt conveyer system, a pair of article receiving and conveying feeder lines extending 55 toward each other from opposite directions and having their delivery ends juxtaposed, each line comprising a plurality of endless belts one of which has a reach extending to the delivery point and the others of which each has a shorter 60 reach opposed to said first mentioned reach with said shorter belt reaches juxtaposed end to end for insertion of articles into said feeder lines between the adjacent ends of said shorter belt reaches, and a belt conveyer line leading trans- 65 versely from the juxtaposed ends of said feeder 70 lines.

lines and comprising a pair of belts having coactive opposed reaches arranged for gripping articles therebetween and conveying them, said latter belts being trained to define an entry mouth for directing articles between the said 5 coacting reaches thereof, and the belts of the feeder lines being trained to deliver the articles into said mouth.

12. In a belt conveyer system, a conveyer line comprising a plurality of endless belts trained 10 to provide a reach of one belt and a pair of directly opposed reaches of other belts therealong juxtaposed end to end to coat therewith to grip and transport articles and to define a constantly open mouth between their juxtaposed ends for 15 entry of articles into the line, means for driving said belts to cause their coactive reaches to travel in the same direction, and belt means for directing articles moving along the lines across the entry mouth gap while at the same time permitting entry of articles to the line through 20 said gap.

13. In a belt conveyer system, a conveyer line comprising a plurality of endless belts trained to provide a reach of one belt and a pair of directly 25 opposed reaches of other belts therealong juxtaposed end to end to coat therewith to grip and transport articles, a pair of pulleys spaced apart along the first belt reach and having said other opposed belts trained around them to define a 30 gap for entry of articles into the line, a pair of pulleys coaxial with and at opposite sides of one of said pulleys at one side of the mouth gap, a pair of pulleys adjacent the pulley at the opposite side of said gap, a pair of belts trained 35 around said latter pairs of pulleys and having reaches coactive with the first reach for directing articles moving along the line across the gap and means for driving all of said belts to cause 40 their coactive reaches to travel in the same direction.

14. In a belt conveyer system, a conveyer line comprising a plurality of endless belts trained to provide a reach of one belt and a pair of directly 45 opposed reaches of other belts juxtaposed end to end to coat therewith to grip and transport articles, a pair of pulleys spaced apart along the first belt reach and having said other opposed belts trained around them to define a gap for entry of 50 articles into the line, a pair of pulleys coaxial with and at opposite sides of one of said pulleys at one side of said gap, a pair of pulleys adjacent the pulley at the opposite side of the gap and spaced therefrom for the admission of articles therebetween, a pair of belts trained around said latter pairs of pulleys and having reaches coactive 55 with the first reach for directing articles moving along the line across the gap, means for driving all of said belts to cause their coactive reaches to travel in the same direction and feeder belt 60 means to deliver articles into the admission space between said adjacent pulleys.

15. In a belt conveyer system, a pick-up conveyer line comprising a plurality of endless belts trained to provide a reach of one belt and a pair 65 of directly opposed reaches of other belts juxtaposed end to end to coat therewith to grip and transport articles, a pair of pulleys spaced apart along the first belt reach and having said other opposed belts trained around them to define a 70 gap for entry of articles into the line, a feeder belt line for delivering articles into said gap including a pair of pulleys adjacent one of said pulleys at one side of said gap and belts trained around said latter pair of pulleys and having op- 75

- posed coactive reaches to grip and transport articles, a pair of pulleys coaxial with and at opposite sides of said pulley at one side of the gap, a pair of pulleys coaxial with and at opposite sides of one of said adjacent feed line pulleys, belts trained around said last-mentioned pairs of pulleys to provide delivery reaches leading from the feeder line obliquely to the pick-up line, the other of said pulleys of the feeder line training its belt for coaction with said delivery reaches, and means for driving all of said belts to cause their coactive reaches to move in the same direction.
16. In a belt conveyer system, a pick-up conveyer line comprising a plurality of endless belts trained to provide a reach of one belt and a pair of directly opposed reaches of other belts juxtaposed end to end to coact therewith to grip and transport articles, a pair of pulleys spaced apart along the first belt reach and having said other opposed belts trained around them to define a gap for entry of articles into the line, a feeder belt line for delivering articles into said gap including a pair of pulleys adjacent one of said pulleys at one side of said gap and belts trained around said latter pair of pulleys and having opposed coactive reaches to grip and transport articles, a pair of pulleys coaxial with and at the opposite sides of said pulley at one side of the gap, a pair of pulleys coaxial with and at opposite sides of one of said adjacent feed line pulleys, belts trained around said last mentioned pairs of pulleys to provide delivery reaches leading from the feeder line obliquely to the pick-up line, the other of said pulleys of the feeder line training its belt for coaction with said delivery reaches, means for driving all of said belts to cause their coactive reaches to move in the same direction, and means for directing articles moving along the pick-up line across said gap.
17. In a belt conveyer system, a pick-up conveyer line comprising a plurality of endless belts trained to provide a reach of one belt and a pair of directly opposed reaches of other belts juxtaposed end to end to coact therewith to grip and transport articles, a pair of pulleys spaced apart along the first belt reach and having said other opposed belts trained around them to define a gap for entry of articles into the line, a feeder belt line for delivering articles into the said gap including a pair of pulleys adjacent one of said pulleys at one side of said gap and belts trained around said latter pair of pulleys and having opposed coactive reaches to grip and transport articles, a pair of pulleys coaxial with and at the opposite sides of said pulley at one side of the gap, a pair of pulleys coaxial with and at opposite sides of one of said adjacent feed line pulleys, belts trained around said last mentioned pairs of pulleys to provide delivery reaches leading from the feeder line obliquely to the pick-up line, the other of said pulleys of the feeder line training its belt for coaction with said delivery reaches, means for driving all of said belts to cause their coactive reaches to move in the same direction, means for directing articles moving along the pick-up line across said gap, comprising a pair of pulleys coaxial and driven with the other of said gap pulleys and at opposite sides thereof, a pair of pulleys adjacent said pair of delivery belts and spaced therefrom for admission of delivered articles, and a pair of belts trained around said pairs of directing pulleys and having reaches opposed to and coactive with said first reach across the gap.

18. In a belt conveyer system, a conveyer line comprising a pair of endless belts trained to provide opposed coacting reaches for gripping and transporting articles and trained to provide reaches diverging from said first reaches and defining a mouth for entry of articles, a conveyer feed belt for delivering articles into said mouth, a pulley within said mouth training said feed belt to provide a reach thereof opposed to and coactive with one of said diverging reaches to deliver articles between the first reaches, and means for driving all of said belts to move their coactive reaches in the same direction.

19. In a belt conveyer system, a conveyer line comprising a pair of endless belts trained to provide opposed coacting reaches for gripping and transporting articles and trained to provide reaches diverging from said first reaches and defining a mouth for entry of articles into the line, a pair of conveyer feed belts leading from opposite directions to said mouth, a pair of pulleys within the mouth training said feed belts to provide reaches thereof opposed to and coactive with said diverging reaches for delivering articles to the first opposed reaches, and means for driving all of said belts to move their coactive reaches in the same direction.

20. In a belt conveyer system, a conveyer line comprising a plurality of endless conveyer belts, and pulleys training said belts to present co-operating reaches arranged in opposed relation for holding sheets therebetween and transporting them along the line, means to drive said belts and move their cooperating reaches in the same direction and at the same speed, a plurality of relatively small pulleys coaxial with and driven with the first mentioned pulleys at the discharge end of the line, a plurality of larger pulleys spaced from the discharge end of the line, and endless belts trained around said small and large pulleys to receive sheets therebetween from the discharge end of the line, deflect them from said conveyer belts and discharge them from between the larger pulleys at a slower speed than their rate of travel along the conveyer line, said larger pulleys having their peripheries closely adjacent to each other and formed to coact for crimping the sheets as they are discharged.

21. A belt conveyer system including a pick-up line comprising a plurality of belts trained to present opposed cooperating belt strands for holding articles therebetween and conveying them along said line, means for driving the belts of the pick-up line, a plurality of feeder lines leading toward said pick-up line for delivery of articles thereto and also comprising a plurality of belts trained to present opposed cooperating belt strands for holding the articles therebetween and conveying them along the feeder line, means for independently driving the belts of each feeder line, and means for rendering each feeder line inoperative without affecting the operation of the other feeder lines and the pick-up line.

22. In a belt conveyer system, a conveyer line comprising a plurality of endless belts trained to provide a reach of one belt and a pair of opposed reaches of other belts juxtaposed end to end to coact therewith to grip and transport articles and to define a mouth between their juxtaposed ends for entry of articles into the line at an intermediate point on said first belt reach, means to drive said belts to cause their coactive reaches to travel in the same direction, and auxiliary belt means to direct articles transported by the line

across said entrance mouth and simultaneously permit entrance of articles through said mouth to the conveyer line.

23. In a belt conveyer system, a conveyer line comprising a plurality of endless belts trained to provide a reach of one belt and a pair of opposed reaches of other belts juxtaposed end to end to coact therewith to grip and transport articles, line pulleys spaced apart along the first belt 10 reach and having said other opposed belts trained around them to define a gap in the line, auxiliary pulleys one coaxial with one of said line pulleys at one side of the gap and the other adjacent the line pulley at the opposite side of the gap 15 and spaced therefrom for the admission of articles therebetween, and an auxiliary belt trained around said auxiliary pulleys and having a reach coactive with the first reach for directing articles along the line across the gap.
24. In a belt conveyer system, a conveyer line comprising a plurality of endless belts trained to provide a reach of one belt and a pair of opposed reaches of other belts juxtaposed end to end to coact therewith to grip and transport articles, 20 line pulleys spaced apart along the first belt reach and having said other opposed belts trained around them to define a gap in the line, auxiliary pulleys one coaxial with one of said line pulleys at one side of the gap and the other adjacent the line pulley at the opposite side of the gap and spaced therefrom for the admission of articles therebetween, an auxiliary belt trained around said auxiliary pulleys and having reaches coactive with the first reach for directing articles 25 along the line across the gap; and power driven feeder means to deliver articles into said admission space.

25. In a belt conveyer system, a pick-up conveyer line comprising a plurality of endless belts trained to provide a reach of one belt and a pair of opposed reaches of other belts juxtaposed end to end to coact therewith to grip and transport articles and to define a mouth between their juxtaposed ends for entry of articles into the line; a transfer belt trained to provide a reach leading obliquely to the pick-up line at said mouth; a feeder conveyer line leading toward said mouth, and having a conveyer belt with a reach oblique to the pick-up line and opposed to said oblique 50 reach of the transfer belt to coact with the latter to transfer articles from the feeder line to the pick-up line; and means to drive all of said coactive belt reaches in the same direction.

26. In a belt conveyer system, a pick-up conveyer line comprising a plurality of endless belts trained to provide a reach of one belt and a pair of opposed reaches of other belts juxtaposed end to end to coact therewith to grip and transport articles and to define a mouth between their juxtaposed ends for entry of articles into the line, a transfer belt trained to provide a reach leading obliquely to the pick-up line at said mouth; a feeder conveyer line leading toward said mouth and having a conveyer belt with a reach oblique 60 to the pick-up line and opposed to said oblique reach of the transfer belt to coact with the latter to transfer articles from the feeder line to the pick-up line; means to drive all of said coactive belt reaches in the same direction, and means 65 to direct articles transported by the pick-up line past said entrance mouth.

27. In combination, a belt sheet conveyer line; and sheet discharge means for said line comprising belts trained to form downwardly converging reaches defining a downwardly tapering dis-

charge chute to receive into its larger upper end sheets discharged from the conveyer line, means to drive the conveyer line at one speed, and means to drive said converging belt reaches downward at a lower speed than that of the conveyer line 5 to discharge the sheets through the lower end of said chute at a reduced speed, said downwardly converging belt reaches being disposed to prevent gripping of the received sheets therebetween before the sheets have been entirely discharged 10 from the conveyer line and to then grip the sheets for positive discharge from the chute.

28. In combination, a belt sheet conveyer line comprising a conveyer line belt trained around a pulley at the discharge point of the line; and sheet discharge means for said line comprising auxiliary belts trained to form downwardly converging reaches defining a downwardly tapering discharge chute to receive into its larger upper end sheets discharged from the conveyer line, 20 means to drive said conveyer line belt at one speed, and means to drive said converging belt reaches downwardly at a lower speed than that of the conveyer line belt to discharge the sheets through the lower end of the chute at a reduced speed, one 25 of said auxiliary belts being trained at the entrance of the chute to deflect the sheets from the line belt at said pulley, said downwardly converging belt reaches being disposed to prevent gripping of the received sheets therebetween before 30 the sheets have been entirely discharged from the conveyer line and to then grip the sheets for positive discharge from the chute.

29. In combination a belt sheet conveyer line comprising belts having opposed line reaches to 35 grip sheets therebetween for conveyance along the line, and pulleys training said belts at a discharge point of the line; and sheet discharge means for said line comprising auxiliary belts trained to form downwardly converging reaches 40 defining a downwardly tapering chute to receive into its larger upper end sheets discharged from the conveyer line, means to drive said conveyer line belts at one speed, and means to drive said converging belt reaches downward at a lower 45 speed than that of the conveyer line belts to discharge the sheets through the lower end of the chute at a reduced speed, said auxiliary belts being trained to deflect the sheets from the conveyer line belts at said pulleys at the discharge 50 point of the line and to prevent gripping of the received sheets between the downwardly converging belt reaches before the sheets have been entirely released from the conveyer line and to then grip the sheets for positive discharge from the 55 chute.

30. In a belt conveyer system, a conveyer line comprising a plurality of endless belts trained to provide a reach of one belt and a pair of opposed reaches of other belts juxtaposed end to end to 60 coact therewith to grip and transport articles and to define a mouth between their juxtaposed ends for entry of articles into the line at an intermediate point on said first belt reach, means to drive said belts to cause their coactive reaches to 65 travel in the same direction, and auxiliary belt means to direct articles transported by the conveyer line across said entrance mouth.

31. In a belt conveyer system, a pick-up conveyer line comprising a plurality of endless belts 70 trained to provide a relatively long reach of one belt and a pair of opposed and shorter reaches of other belts therealong juxtaposed end to end to coact therewith to grip and transport articles and to define a mouth between the juxtaposed ends of 75

said shorter reaches for entry of articles into the pick-up line at an intermediate point on said relatively long reach, means for driving said belts to cause the coacting relatively long belt reach and shorter belt reaches to travel in the same direction, a feeder conveyer line running toward the said intermediate entry mouth of the pick-up line, means forming a delivery connection between said feeder line and pick-up line at said mouth, and auxiliary belt means to direct articles conveyed by the pick-up line past said entry mouth.

32. In combination, a belt sheet conveyer line; and sheet discharge means for said line comprising belts trained to form downwardly converging reaches defining a downwardly tapering dis-

charge chute to receive into its larger upper end sheets discharged from the conveyer line, means to drive the conveyer line at one speed, means to drive said converging belt reaches downward at a lower speed than that of the conveyer line to discharge the sheets through the lower end of said chute at a reduced speed, said downwardly converging belt reaches being disposed to prevent gripping of the received sheets therebetween before the sheets have been entirely discharged from the conveyer line and to then grip the sheets for positive discharge from the chute, and means at the discharge end of said chute to crimp the sheets before they are discharged.
